(57) CLAIM

The ornamental design for a massage wand, as shown and described.

DESCRIPTION

FIG. 1 illustrates a front perspective view of a massage wand;

FIG. 2 illustrates a bottom perspective view of the massage wand thereof;

FIG. 3 illustrates a rotated view of the front perspective of the massage wand thereof;

FIG. 4 illustrates a front view of the massage wand thereof;

FIG. 5 illustrates a back view of the massage wand thereof;

FIG. 6 illustrates a left side view of the massage wand thereof;

FIG. 7 illustrates a right side view of the massage wand thereof;

FIG. 8 illustrates a top view of the massage wand thereof; and,

FIG. 9 illustrates a bottom view of the massage wand thereof.

The broken lines shown in the drawings are for the purpose of illustrating portions of the massage wand, which form no part of the claimed design.
